SELECTIVE CIRCUIT CONTROLLING SYSTEM

Filed April 12, 1924

Inventor:
Benjamin W. Jones,
by Alexander S. Jones
His Attorney.

UNITED STATES PATENT OFFICE.

BENJAMIN W. JONES, OF SCHENECTADY, NEW YORK, ASSIGNOR TO GENERAL ELECTRIC COMPANY, A CORPORATION OF NEW YORK.

SELECTIVE-CIRCUIT-CONTROLLING SYSTEM.

Application filed April 12, 1924. Serial No. 706,190.

My invention relates to improvements in the selective control of electric circuits, particularly the circuits of a plurality of electric translating devices that are to be selectively energized from a common supply conductor by the energization and deenergization of the conductor itself.

The principal object of the present invention is the provision of an improved control arrangement that insures energization of a predetermined portion of the devices upon the energization of the supply conductor after a substantial period of deenergization while permitting the selective energization of a different portion of the devices by momentarily deenergizing the supply conductor.

A further object of the invention is the provision of a control system of the above character wherein an improved form of electroresponsive controlling device, such as claimed in my divisional application, Serial No. 75,111, filed December 12, 1925, may be employed advantageously.

Although my improved selective control system may be readily adapted for various uses, it has particular advantage in systems for controlling the selective operation of a plurality of electric translating devices, such as systems for selectively controlling the lighting of lamps of different candle power.

Under certain conditions, it is advisable to provide a comparatively high degree of illumination for a portion of the time and a comparatively low degree of illumination during another portion of the time that it is desired to have artificial illumination. An example of this is found in street lighting systems in which at each point of illumination there is provided a large high candle power lamp and a low candle power lamp, ordinarily in the same globe. The high candle power lamp is intended to be operated during the earlier part of the night during which there would ordinarily be a greater demand for good illumination, and the small lamp for the remainder of the night during which a comparatively small amount of artificial illumination is needed.

Another of the objects of my invention is to provide a simple and effective arrangement whereby by simply opening and closing the circuit which feeds the translating devices, such as lamps or the like, the desired selection of the portion of the translating de-

vices which is to be energized from the supply conductor is automatically accomplished.

A further object of the invention is to provide a selective control system wherein the selective controlling devices will all return to similar positions when the supply circuit is opened for a sufficient interval of time.

In carrying my invention into effect in a selective control system and in the form which I now regard as the preferred form, I provide an electroresponsive switch mechanism, preferably of the improved form described and claimed in my divisional application, Serial No. 75,111, filed December 12, 1925, which is operated to automatically switch from one translating device to another under the control of some means for regulating the supply of energy to the translating devices, as, for example, a switch included in the supply conductor which feeds the translating devices. The switching device is preferably arranged so as to be biased to the circuit closing position to which it is last operated and is operated to the next circuit closing position in succession under the control of a thermal responsive element which, in turn, is under the control of the switch or other means for controlling the energization of the translating device.

For a better understanding of my invention, reference is had to the accompanying drawing, wherein I have illustrated in very diagrammatic form an arrangement which I now regard as the preferred form of the invention.

Referring to the drawing, the translating devices to be selectively controlled are indicated as the lamps 10, 11, 12 and 13, the lamps 10 and 12 being of comparatively high candle power and the lamps 11 and 13 of comparatively low candle power. The two lamps 10 and 11 comprising one set will ordinarily be located at some distance from the similar set of lamps 12 and 13, each set of lamps forming a single point of illumination. The set of lamps 10-11 is selectively controlled by means of the selective switching device 14. This device comprises a pivoted switch member 15 which has a plurality of circuit closing positions, and which is biased to the position to which it is last thrown by means of a spring 16. By reason of the location of the pivot for the switch member 15, the connection of the spring 16 with the switch member and the point of connection of the other end

of the spring, the arrangement forms an over-center device which operates to effect a quick closing of the circuit and to serve as a means for biasing the switch member in the position 5 to which it is last thrown. The switch member is operated from one circuit closing position to the other under the control of the thermal responsive element 17, which is indicated as a bi-metallic thermostat heated by 10 the resistor 18 thermally related therewith. The switch member 15 in the position indicated in the drawing is arranged to complete the circuit for the large lamp 10 and thus establish an energizing circuit for this lamp 15 from the secondary of the transformer 19 included in the circuit of the supply conductor 20. The electromagnet 21 is provided for magnetically holding the switch member in the position shown so that during the time 20 in which it is desired to have the comparatively large value of illumination, the switch member will be magnetically held in position and thus practically eliminate the effects of jars and shocks in opening the circuit of the 25 large lamp 10. In the other position of the switch member, the large lamp 10 is deenergized and the small lamp 11 is energized. The lamps 12 and 13 are controlled by a similar selective switching device and I have indicated this in the drawing to disclose the fact 30 that the invention is applicable to the control of any desired number of sets of translating devices.

It will be observed that I have indicated 35 the system as an alternating current system in which the lamps are energized from the secondaries of current transformers, although I would have it understood that the invention is not necessarily limited to an alternating current system, since the invention is 40 equally applicable to a direct current system, as will be understood by those skilled in the art from an understanding of the invention.

As thus constructed and arranged and with 45 the parts in the respective positions shown in the drawing, the operation of the invention is as follows:

Upon closing the disconnecting switch 22, which is employed to regulate the supply of 50 energy to the supply conductor 20, the lamps 10 and 12 will receive energy from the supply conductor and the thermostats 17 and 23 will be heated responsively to the current taken by their respective controlled lamps. Inasmuch as lamps 12 and 13 are controlled in a 55 manner identical with the control of the lamps 10 and 11, I shall describe merely the operation of the selective switching device 14. When the thermostat 17 is heated by the resistor 18, it will flex and attempt to turn the 60 switch member 15 clockwise about the pivot of the switch member against the action of the biasing spring 16 and against the holding effect of the electromagnet 21. As long as 65 the supply of energy to the lamp 10 continues

the electromagnet 21 will prevent the switch member from being thrown to its other circuit closing position by the thermostat.

In order to extinguish the large lamp 10 and energize the small lamp 11, the disconnecting switch 22 will be opened, thereby de-energizing the lamp 10 and the holding electromagnet 21. By reason of the fact that the thermostat 17 is flexed and will retain its heat for an appreciable interval, the flexing 75 force of the thermostat prevails to act on the switch member 15 and turn this switch member clockwise against the action of the biasing spring 16 until the switch member is over center. When the switch member is thrown over center, the biasing spring 16 takes control of the same and operates the switch member quickly to the circuit closing position and holds the same in that position. The interruption of the circuit for the large lamp 10, 80 and the completion of the circuit for the small lamp 11 will take a very small interval of time, so that if the switch 22 is again closed after a brief interval, the lamp 11 will receive energy instead of the lamp 10. The current 85 through the lamp 11 passes through the resistor or other heating device 18, so that the thermostat 17 is again flexed, but the flexing of this thermostat produces no effect on the operation of the switch member at this time. 90 However, if the disconnecting switch 22 is again opened, the thermostat will attempt to straighten due to the cooling thereof and thus operate against the biasing action of the spring 16 to turn the switch member 15 counter-clockwise about its pivot. When the switch member is moved over center, the biasing spring 16 will take over the operation of the switch member and cause the switch member to be moved quickly to the position indicated in the drawing, ready for the next operation. 95

It will be apparent from the above that by a proper operation of the disconnecting switch 22, the thermal responsive selective device 14 will be caused to automatically select the desired illumination. If, for any reason, the supply of power should fail, and the selective switching device thus operates to establish a selection not desired, the operator may very quickly establish the desired illumination by the operation of the disconnecting switch 22. Thus, the disconnecting switch 22 may be located in a power house 100 and under the control of the attendant for the electrical apparatus therein. Under some conditions, it may be desirable to have one set of lamps in the power house so that the attendant can, at all times determine the illumination which is present in a system which 105 may be located at some distance from the power plant. 110

It will be observed that in case the switching devices for any reason do not all respond similarly to the opening and closing of the 115 120 125 130

disconnecting switch 22; in other words, at certain points of illumination the large lamps are lit whereas at other points the small lamps are lit, if the disconnecting switch 22 is retained open for a sufficient interval of time all of the switching devices which are not in the position shown on the drawing will be automatically returned thereto by reason of the cooling of the thermostats. Thus, even though the synchronous operation of the switching devices does not proceed as intended during the night, the switching devices will all be in similar positions ready for correct initial operation the following night.

What I claim as new and desire to secure by Letters Patent of the United States, is:—

1. The combination of a plurality of electric translating devices, a supply conductor for said devices, and electroresponsive controlling switch mechanism interconnected with said devices and conductor and selectively operable to effect the separate energization of different portions of said devices in accordance with different periods of deenergization of the conductor following energization of each portion of the translating devices.

2. The combination of a plurality of electric translating devices, a supply conductor for said devices, and electroresponsive switch mechanism for separately energizing different portions of said devices from said conductor and arranged to effect the separate energization of a predetermined portion of said devices upon reenergization of said conductor after a substantial period of deenergization following energization of each portion of said devices and to effect the separate energization of a different portion of said devices upon reenergization of the supply conductor after a momentary deenergization thereof following energization of each portion of said devices.

3. The combination of a pair of electric translating devices, a supply conductor for said devices, and electroresponsive switch mechanism interconnected with said devices and said conductor and having a thermal responsive operating member movable between two positions for operating said switch mechanism to effect energization of different portions of said devices upon reenergization of the conductor after correspondingly different periods of deenergization thereof following a period of energization of each portion of said translating devices.

4. The combination of a plurality of electric translating devices, a supply conductor for said devices, and electroresponsive switch mechanism interconnected with said conductor and having a thermal current responsive operating means operable during deenergization of the supply conductor responsive to the heating effect of prior energization of

the conductor to effect the separate energization of a predetermined portion of said devices upon reenergization of the conductor only after a limited period of deenergization of the conductor.

5. The combination of a plurality of electric translating devices, a supply conductor for said devices, and electroresponsive switch mechanism interconnected with said conductor and said devices and having a movable circuit controlling member biased to one circuit closing position to effect the separate energization of a predetermined portion of said devices upon the initial energization of said conductor, said movable circuit controlling member being operable to the second circuit closing position upon deenergization of the supply conductor responsively to the heating effect of prior energization of the conductor to effect the separate energization of a different portion of said devices upon reenergization thereof within a limited time interval.

6. The combination of a plurality of electric translating devices, a supply conductor for said devices, electroresponsive switch mechanism connected to be energized from said circuit and arranged to operate from a predetermined circuit controlling position to another circuit controlling position during deenergization of said conductor responsive to the heating effect of prior energization of the conductor, and connections controlled by said switch mechanism through which different portions of said translating devices are separately energized in each circuit controlling position of said switch mechanism.

7. The combination of a plurality of electric translating devices, a supply circuit therefor, an electroresponsive switch mechanism connected to be energized from said circuit and biased to a predetermined circuit controlling position and having a thermal current responsive element arranged to operate the switch mechanism from said predetermined position to another circuit controlling position and maintain the switch mechanism therein for a limited time interval during deenergization of said circuit and to maintain the switch mechanism in said other circuit controlling position upon reenergization of the circuit within said time interval, and connections controlled by said switch mechanism through which different portions of said devices are separately energized in each of said circuit controlling positions.

8. The combination of a plurality of electric translating devices, a supply circuit therefor, an electroresponsive switch mechanism interconnected with said circuit and said devices and biased to effect the separate energization of a predetermined portion of said devices upon the initial energization of said circuit, said switch mechanism being provided with a thermal responsive element ar-

ranged to be electrically heated during energization of said predetermined portion of said devices for effecting operation of the switch mechanism to a different circuit controlling 5 position upon deenergization and quick reenergization of said circuit, and connections through which a different portion of said devices are separately energized and said thermostatic element is electrically heated upon 10 reenergization of said circuit during said time interval.

9. The combination in a selective control system of a supply conductor, a plurality of translating devices, a selective circuit controlling device for connecting the translating devices to be separately energized from the supply conductor, said circuit controlling device having a thermal responsive movable operating element connected to be heated when 15 each translating device is energized from the supply conductor for automatically selecting the translating device to be next energized from the supply conductor in accordance with different periods of cooling of the thermal responsive element, and means for controlling the supply of energy to the translating devices for controlling the cooling of the said thermal responsive operating element to determine the translating device to be energized 20 from the supply conductor.

10. The combination in a selective control system of a supply conductor, a plurality of translating devices adapted to be separately energized from the supply conductor, a thermal responsive circuit controlling device selectively operable between a plurality of circuit closing positions in accordance with different periods of heating and cooling thereof for energizing the translating devices separately 25 from the supply conductor, and means for controlling the heating and cooling of the said thermal device to control the selection of the next translating device to be energized 30

from the supply conductor following energization of each one of said translating devices.

11. The combination in a selective control system of a supply conductor, a plurality of translating devices adapted to be separately energized from the supply conductor, a selective circuit controlling device having a plurality of circuit closing positions and biased to each position when operated there-to, for energizing the translating devices separately from the supply conductor, the said selective device having a thermal responsive movable member for operating the selective device against the bias thereof, and means for controlling the supply of energy to the supply conductor for controlling the operation of said member to control the selection of said devices to be energized from the supply conductor following energization of each one of said translating devices. 55

12. The combination in a selective control system of a supply conductor, two lamps arranged to receive energy from the supply conductor, a switching device for selectively energizing the said lamps separately from the supply conductor, the said device having a thermostatic operating element arranged to be heated by the current taken by a lamp 65 and a switch member biased to each of two circuit closing positions when operated there-to by the thermostatic element when the supply of energy ceases, electromagnetic means for holding the said switch member in an 70 operated position, and a switch for cutting off the supply of energy to said conductor to cause the said thermostatic element to operate the said switch member to select the other of said lamps to be energized from the supply conductor. 75

In witness whereof, I have hereunto set my hand this 11th day of April, 1924.

BENJAMIN W. JONES.
